WINDMILL GUIDE DEVICE

Arthur L. Ligon, Fort Stockton, Tex.

Application October 19, 1933, Serial No. 694,334

6 Claims. (Cl. 308—3)

This invention relates to a guide device for the pump rod of a windmill or the like, and it constitutes an improvement of the construction disclosed in Letters Patent No. 1,753,126 issued to me on April 1st, 1930.

A primary object of the present invention is to provide novel means enabling automatic relative movement of parts of the guide device in the event said pump rod should break above the guide device, so that in falling, the pump rod will not cause breakage of any part of the guide device or of the derrick or tower of the windmill or the like.

It is also aimed to provide a novel construction of guide board enabling expeditious adjustment to accommodate the guide device, irrespective of the length of the girts or frame members which support the guide board.

Various additional objects and advantages will in part be pointed out and become apparent from a consideration of the description following taken in connection with accompanying drawing illustrating an operative embodiment.

In said drawing:

25 Figure 1 is a fragmentary side elevation of windmill parts showing my improvements in operative position,

Figure 2 is an elevation taken at a right angle to Figure 1,

30 Figure 3 is a horizontal sectional view taken on the line 3—3 of Figure 1, and

Figure 4 is a vertical sectional view taken on the line 4—4 of Figure 1.

Referring specifically to the drawing, where-in like reference characters designate like or similar parts, 10 designates a conventional derrick or tower of a windmill of which 11 are horizontal cross members or girts. 12 designates the usual vertically reciprocable pump rod actuated by the windmill or parts located at the top of the derrick constituting no part of my invention, and therefore unnecessary to illustrate.

The guide device comprises a bracket 13 having socket portions 14 in which are rigidly secured in any suitable manner, a pair of vertical, parallel guide rods 15. The upper ends of the guide rods 15 extend into sockets 16 of a bracket 16', pivotally secured by a horizontal axis member or pin 17 to a cleat 18. Disposed between the bracket 13 and cleat 18 and against the pump rod 12 is a metallic strap 19, and a bolt 20 passes through the bracket 13, strap 19, and pump rod 12 while a bolt 21 passes through the cleat 18, strap 19, and pump rod 12. An addi-

tional fastening 22 may pass through the cleat 18, and strap 19 into the pump rod 12. A leaf spring 23 is fastened by elements 24 passing through the strap 19 and is so arranged as to bear against a lug or part 25 of the bracket 16', to normally urge it into operative position as shown in Figures 1 and 2, but in the event of breakage of the pump rod 12 above the guide device, to enable the bracket 16' to swing against the tension of the spring 23 to the position shown in Figure 4, thereby avoiding breakage of any of the adjacent parts of the guide device or derrick.

A guide board or yoke which cooperates with the parts described is shown at 26 and consists of independent relatively slidable elements 27 of wood, metal or the like. Each member 27 has an elongated slot 28 therein adjacent one end, through which hook bolts 29 pass, and which are engaged with an adjacent girt or cross member 11 of the derrick. Suitable nuts 30 are threaded on said bolts 29 above and adapted for binding engagement with the members 27. Transverse bolts 31 pass through various aligned holes in the board members 27 and at the ends of such holes, notches 32 are provided which accommodate metallic blocks or U-shaped elements 33 against which the heads 34 and nuts 35 on such bolts are tightened.

Along opposite longitudinal edges of the members 27, notches 36 are provided, in two of which, according to the relative adjustment of the members 27, the guide rods 15 are disposed for relatively loose vertical sliding movement with the pump rod 12. To this end, the nuts 30 are not tightened until the guide board 26 has been arranged with the guide rods 15 operative in two of the notches 36. A latch or button 37 is adapted to extend across those notches 36 engaged by the rods 15. Such latch 37 is secured in place by a bolt 38, enabling the latch to be swung to a vertical position as guide board 26 is moved into engagement with the rods 15, after which such latch may be swung behind the rods 15 into the position shown in the drawing. A nut 39 is applied to the bolt 38. In order to brace the latch or button 37, a metallic strap 40 is secured thereto in any suitable manner and an end thereof as at 41 is forked or bifurcated so that when the latch is in applied position, one portion of the fork will engage the under surface and the other part of the fork will engage the upper surface of the adjacent member 27, thereby preventing accidental turning of the latch on the bolt 39.

As a result of the construction described, the adjustable guide board 26 enables a single guide board to be attached to various derricks or towers regardless of the length of the supporting members or girts 11, or the distance between them. Should the pump rod 12 break from above the guide device, through the falling of such pump rod, bracket 16' will strike a guide board, causing the bracket 16' to move to the right out of the path of the guide board, as shown in Figure 4, thus permitting descent of the pump rod without suspension on or impact with the guide board or any part of the invention or derrick to avoid breaking or injury to any of its parts.

The nuts 30 and 39 may be provided with handles at 42 and 43, respectively, to enable manual operation of the device.

Various changes may be resorted to provided they fall within the spirit and scope of the invention.

I claim as my invention:—

1. In combination with a vertically reciprocating member, and a structure relatively to which it reciprocates, a guide mechanism having parts in interengagement and supported on said reciprocating member and structure, a part of said mechanism being displaceable automatically through engagement with another part of said mechanism upon descent of the reciprocating member following breakage above the guide mechanism.

2. In combination with a vertically reciprocating pump rod, a derrick associated therewith, a guide rod device carried by the reciprocating pump rod, a guide yoke engaged by the rod device and carried by the derrick, means engaging the rod device above the guide yoke and movably connected to the pump rod, said guide yoke being in the path of the downward movement of said means, whereby upon falling of the pump rod after breakage, the guide yoke will be automatically disengaged by the guide rod device.

3. A device of the class described comprising guide rods, a bracket adjacent the lower ends thereof to mount the rods, a bracket engageable with the upper ends of the rods, means

5 pivotally mount the last mentioned bracket, said last mentioned bracket having a projection, spring means engaging the projection normally urging the last mentioned bracket into engagement with the rods, and a guide yoke through which the rods pass adapted for engagement by the second mentioned bracket through undue downward movement of the rods to automatically release the rods.

4. A device of the class described comprising 10 guide rods, a bracket adjacent the lower ends thereof to mount the rods, a bracket engageable with the upper ends of the rods, means to pivotally mount the last mentioned bracket, said last mentioned bracket having a projection, 15 spring means engaging the projection normally urging the last mentioned bracket into engagement with the rods, a guide yoke through which the rods pass adapted for engagement by the second mentioned bracket through undue downward movement of the rods to automatically release the rods, a strap, and fastenings passing through the bracket and strap to operatively connect them to a reciprocating member.

5. In a device of the class described, a guide 25 rod attachable to a reciprocating member, said guide rod having a free end, a displaceable element engaging said free end of the guide rod, a yoke slidably engaged by said guide rod below said displaceable element, so that the yoke will 30 displace said element through undue lowering of the guide rod and said guide rod will move below and automatically disengage the yoke.

6. In a device of the class described, a guide 35 rod attachable to a reciprocating member, said guide rod having a free end, a displaceable element engaging said free end of the guide rod, a yoke slidably engaged by said guide rod below said displaceable element, so that the yoke will 40 displace said element through undue lowering of the guide rod and said guide rod will move below and automatically disengage the yoke, said yoke having a notch in an edge thereof to receive the guide rod, and latch means on the yoke disposable over the notch.

45 ARTHUR L. LIGON.
